JOHN G. LOCKE, OF PASSAIC, NEW JERSEY.

WINDOW-LOCKING DEVICE.

1,137,502.

Specification of Letters Patent. Patented Apr. 27, 1915.

Application filed April 29, 1913. Serial No. 764,329.

To all whom it may concern:

Be it known that I, JOHN G. LOCKE, a citizen of the United States, residing at Passaic, in the county of Passaic and State 5 of New Jersey, have invented certain new and useful Improvements in Window-Locking Devices; and I do hereby declare the following to be a full, clear, and exact description of the invention, such as will enable others skilled in the art to which it 10 appertains to make and use the same, reference being had to the accompanying drawings, and to characters of reference marked thereon, which form a part of this specification.

The present invention has reference, generally, to improvements in locking device for sash-windows and the like; and the invention relates, more particularly, to simple, 20 cheap, efficient and easily manipulated locking device for sash-windows which serves to securely lock the window-sashes when in closed position, and also to securely lock the window-sashes in partially open position 25 against a further opening of the same, when it is desired to have the window-sashes partly open for the purpose of securing interior ventilation.

The present invention has for its principal object to provide a simple and easily operated window locking device, which will in operation automatically lock the window-sashes when the same are moved into their closed position in the window frame and 30 which will also permit the window-sashes to be partially opened to obtain ventilation, but which will still maintain the same locked against further opening when in such partially opened or ventilating position, said 35 locking device being proof against manipulation or tampering with from the exterior of the window, when in either locking position, unless the window itself is destroyed.

A further object of the present invention 40 is to provide in connection with a window locking device of the character above described, a means for releasing the bolt element of the locking device from its operative position so that the window-sashes may be 45 completely opened.

Other objects of the present invention not at this time more particularly enumerated, will be clearly understood from the following detailed description of the present invention.

With the various objects of this invention

in view, the same consists, primarily, in the novel window locking-device hereinafter set forth; and, furthermore, this invention consists in the novel arrangements and combinations of the various devices and parts, as well as in the details of the construction thereof, all of which will be hereinafter more fully described in the following specification, and then finally embodied in the 60 clauses of the claim which are appended to and which form an essential part of this specification.

The invention is clearly illustrated in the accompanying drawings, in which:—

Figure 1 is a face view of a window with the sashes thereof in closed position, and the novel locking device, made according to and embodying the principles of the present invention, being shown in operative connection with said window sashes and in normally locking relation thereto; Fig. 2 is a similar view illustrating said locking device in locking position when retaining said window-sashes in partially open position for 80 the purpose of securing interior ventilation. Fig. 3 is an enlarged detail perspective view of the novel locking device in operative connection with the sashes of a window, the latter being shown in closed position and the 85 locking-device in its automatically locking position. Fig. 4 is an enlarged detail longitudinal section taken on line 4—4 in said Fig. 1 looking in the direction of the arrow α ; Fig. 5 is a similar longitudinal section 90 taken on line 5—5 in said Fig. 2, also looking in the direction of the arrow α ; and Fig. 6 is a similar longitudinal section illustrating the operation of the means for releasing the bolt element from operative relation 95 with the bolt receiving element of the locking device, so that said window sashes may be completely or entirely opened.

Similar characters of reference are employed in all of the hereinabove described 100 views, to indicate corresponding parts.

Referring now to the said drawings, the reference character 1 indicates a window-frame in which are slidably mounted, in the usual manner, an upper window sash 2 and a lower window sash 3. Secured, in suitable position, to the meeting-rail 4 of said lower window-sash 3, by means of its screw-threaded shank 5 which screws into said meeting rail, is an eye-member 6, to 105 which is pivotally connected or anchored, by means of its link-end 7 a bolt-element 8.

The free end of said bolt element 8 is provided with a transversely extending head-portion 9, preferably of T-shaped, although if desired the same may be made L-shaped, 5 or in any other suitable form.

The reference character 10 indicates a supporting or bracket portion of a bolt receiving element, the same being designed to be connected with and supported upon one 10 of the vertical stiles 11 of said upper window-sash 2 by said supporting or bracket-portion 10, and to this end said supporting or bracket-portion may be provided with two or more perforated tongues or lugs 12, 15 through the perforations of which the fastening screws 13 may be passed and screwed into said vertical stile 11. Integrally connected with the inner edge of said supporting or bracket-portion 10 is an off-set portion 14, the same extending inwardly along the inner edge of said stile 11, and connected with said off-set portion 14 is the 20 guard or keeper-plate 15 of the said bolt-receiving element, the same being positioned 25 to project outwardly from the inner side of said stile 11, and disposed to extend longitudinally of said stile 11. Connected with said guard or keeper-plate 15 is a back or body-plate 16, the same being spaced rearwardly from said guard or keeper-plate 15 and paralleling the same so as to provide an intervening space or runway 17. Said guard or keeper-plate 15 and said back or body-plate 16 are connected together at their 30 upper ends by an end-member 18, which may be formed integrally with said respective plates, or which may be inserted between the same and thus secured, said end-member providing a stop at the upper end of said 35 space or runway 17 provided between said respective plates. Formed adjacent to the lower end of said back or body-plate 16 is a rearwardly bent or pressed portion 19 adapted to provide in said back or body-plate a suitably located depression or seat 20. The extreme lower end 21 of said back or body-plate 16, below said depression or seat 20, is bent forward so as to lie in contact with the lower end of said guard or 40 keeper-plate 15, to which it is secured by rivets, or any other suitable fastening means. In order to secure even greater strength at the jointure of the lower ends of said back or body-plate and said guard or keeper-plate 15, the end of said back or body-plate may be bent around the end of said keeper-plate as at 22. Integrally formed with said back or body-plate 16 so 45 as to extend from the longitudinal free edge 50 of the same is a side-portion 23 which is bent to extend over or across the intervening space or runway 17, at one side thereof, the marginal edge 24 of said side-portion 23 being turned over to engage the marginal edge of said guard or keeper-plate 15 as

shown, or if desired said side-plate may be made to extend from said keeper-plate, or from both keeper-plate and back or body-plate in various ways, so as to serve the purpose of closing the side of said space or runway 17, and strengthening the assembled relation of said back or body-plate and guard or keeper-plate, hence I do not limit myself to the particular arrangement of side-portion shown in the accompanying drawings. Formed in said guard or keeper-plate 15 is a longitudinally extending slot or opening 25. Also formed in said guard or keeper-plate 15 adjacent to lower end of said slot or opening 25 is a 55 hatch portion formed by the cutaway portion 26 at the left marginal edge of said slot or opening, and the cutaway portion 27 at the right marginal edge of said slot or opening. Said hatch serves as a means of entrance and exit for said head-portion 9 of said bolt-element 8 into said space or runway 17 and in engagement with said back or body-plate 16. A spring-member or plate 28 is secured by riveting or otherwise 60 at its lower end to the lower ends of said back or body-plate and guard or keeper-plate, the same extending upwardly so that its body lies across said cutaway portion 27 thus normally closing said hatch against the removal therethrough of said head-portion 9 of said bolt-element when the latter is inserted or arranged operatively within said 65 space or runway 17. A push-button 29 is connected with said spring-member or plate 28 whereby the same may be depressed, in the manner shown in Fig. 6 of the drawings, thereby permitting said head-portion 9 to ride up over said spring-member or plate and then be thrown out or removed through 70 said hatch. To this end the free end of said spring-member or plate 28 is so located as to contact with said back or body-plate when depressed at a point above the location of said depression or seat 20. Suitably located upon and connected with said meeting-rail 4 of said lower window-sash 3 is a bolt-holder 30 which receives and holds the 75 said bolt-element 8 when the same is disengaged from its operative association with said bolt-receiving element, (as shown by dotted lines in Figs. 1 and 3) thus preventing the same rattling or moving about its pivotal connection when not in use, and when thus arranged assuring freedom of 80 movement to the window-sashes when it is desired to fully or completely open either 85 one or the other or both of the same.

While I have shown and described a construction of my novel locking-device which is adapted to be secured externally to the stile of the upper window-sash, it will also be clearly evident that when so desired, the novel bolt-receiving element may be counter sunk in said stile so that said guard or 90

keeper-plate 15 is flush with the stile surface, and when so arranged it will be obvious that the bracket-portion 10 and off-set portion 14 may be dispensed with.

5 Having thus described the construction of my novel locking device I will now set forth the manner and advantages of its use when in operation.

When the window sashes are closed the 10 hatch in the keeper-plate 15 of said bolt receiving element is so located with reference to the free end of said bolt-element 8, that the latter's head-portion 9 may be inserted therethrough and by pushing against the same 15 said spring member or plate 28, is depressed so that said head-portion 9 will pass through said hatch. Now by either slightly raising the lower window-sash 3, or lowering the upper window-sash 2 the head-portion 9 is 20 caused to ride along the surface of said spring-member or plate 28 and thus enter said space or runway 17, where the same contacts with said back or body-plate while the shank of said bolt-element rides in the 25 slot or opening 25. When the said head-portion 9 passes the end of said spring-member or plate 28, the latter springs back to normal initial position thus closing said hatch against the removal of said head-portion 30 of the bolt-element from said space or runway 17 until said spring-member or plate 28 is again depressed to permit the same to ride up thereon and out through the hatch as above described. When the said bolt-element 35 8 with its head-portion 9 is thus arranged to ride in said space or runway 17 the window-sashes may be closed and then said head-portion 9, owing to the inclined disposition of said bolt-element 8, falls into 40 said depression or seat 20 formed in said back or body-plate 16. When thus positioned said bolt-element serves to automatically lock the window-sashes against being 45 opened, by reason of the stopped engagement of said head-portion 9 with said seat or depression 20, and any attempt to raise the lower window-sash 3 merely forces more firmly into the said seat or depression 20 the head-portion 9 of the bolt-element, or any 50 attempt to lower the upper window-sash 2 merely forces the said seat or depression 20 more firmly against the head-portion 9 of said bolt-element. Now if it is desired to 55 open either or both window-sashes partially for the purpose of admitting air for interior ventilation through the window, the said bolt-element 8 is oscillated to remove said head-portion 9 out of said depression or seat 20 and into said space or runway 17. This 60 being done a limited movement of the sashes is permitted, the movement being stopped or limited by the engagement of said head-portion 9 with the stop formed by the end member 18 which joins the upper end of 65 said back or body-plate 16 and said guard

or keeper-plate 15 thus closing the upper end of said space or runway 17. Of course any movement of the lower window-sash 3 pushes or slides the head-portion upwardly through the space or runway 17 until it is 70 stopped by engagement with said end-member 18, and any movement of the upper window-sash 2 pushes or slides the bolt receiving element upon said head-portion until the end-member 18 engages said head-portion, in both cases the shank of the bolt-element 8 rides in said slot or opening 25 which is wide enough to permit its free movement, but which is not wide enough to permit the removal of the widened head-portion 9 therethrough. It will thus be apparent that while such a limited opening of either or both window-sashes is obtainable, nevertheless the respective sashes are still maintained in such a locked condition as 80 will prevent a full or complete opening of the same sufficiently wide to permit entrance from the outside of the window. It will also be apparent that the locking device can not be tampered with from the exterior of 85 the window when the same is thus partially opened for ventilation, since the head-portion 9 of the bolt-element can not be removed from the runway 17, and if the sashes are closed the said bolt-element immediately is 90 engaged by the seat or depression 20, so that the sashes become at once automatically locked against even the limited opening permitted, unless the bolt-element is withdrawn from said depression or seat 20, by manipulation from inside of the window only, as 95 above described.

It will thus be clearly evident that my present invention provides a very simple, strong, cheap and efficient locking-device 105 which permits a limited opening of the window-sashes for the purposes of ventilation.

I am aware that some changes may be made in the general arrangements and combinations of the several devices and parts, as well as in the details of the construction of the same, without departing from the scope of the present invention as set forth in the foregoing specification. Hence, I do 110 not limit my present invention to the exact arrangements and combinations of the various devices and parts as described in the said specification, nor do I confine myself to the exact arrangements or details of the 115 construction of the said parts as illustrated in the accompanying drawings.

I claim:—

1. In a device of the kind described a pivoted bolt element for connection with one 125 window-sash, an enlarged head connected with the free end of said bolt element, a bolt-receiving element comprising a slotted plate in which the free end of said bolt element may be inserted, a bracket-plate con- 130

- 5 nected with said slotted plate and off-set therefrom whereby said slotted plate may be secured to and offset from a vertical stile of the other window-sash, a body-plate connected with and rearwardly spaced from said slotted-plate to provide a runway in which said head of said bolt element rides, and a depressed portion providing a shoulder in said body-plate adjacent to its 10 lower end with which said head of said bolt element engages when the window-sashes are in closed position, and by means of which said window-sashes are automatically locked when closed.
- 15 2. In a device of the kind described a pivoted bolt element for connection with one window-sash, an enlarged head connected with the free end of said bolt element, a bolt-receiving element comprising 20 a slotted plate in which the free end of said bolt element may be inserted, a bracket-plate connected with said slotted plate and off-set therefrom whereby said slotted plate may be secured to and offset from a vertical 25 stile of the other window-sash, a body-plate formed integrally with said slotted-plate and doubled back upon the latter so as to be spaced rearwardly therefrom to provide a runway in which said head of said bolt 30 rides, and a side-portion connected with said body-plate, the same being bent forwardly and over a side marginal edge of said slotted plate to secure the said body-plate in fixed position with relation to said slotted-plate.
3. In a device of the kind described a 35 pivoted bolt element for connection with one window-sash, an enlarged head connected with the free end of said bolt element, a bolt-receiving element comprising a slotted plate in which the free end of said bolt element may be inserted, a bracket-plate connected with said slotted plate and offset therefrom whereby said slotted plate may be secured to and offset from a vertical stile of the other window-sash, a body-plate formed 40 integrally with said slotted-plate and doubled back upon the latter so as to be spaced rearwardly therefrom to provide a runway in which said head of said bolt rides, a side-portion connected with said body-plate, the same being bent forwardly and over a side marginal edge of said slotted plate to secure the said body-plate in fixed 45 position with relation to said slotted-plate, and a depressed portion providing a shoulder in said body-plate adjacent to its lower end with which said head of said bolt element engages when the window-sashes are in closed position, and by means of which said window-sashes are automatically locked 50 when closed.
- 55 In testimony, that I claim the invention set forth above I have hereunto set my hand this 26th day of April, 1913.
- JOHN G. LOCKE.
